INVENTOR:

William Grattan,
By his Attorney

Arthur C. Stasor Loring

UNITED STATES PATENT OFFICE.

WILLIAM GRATTAN, OF DOOKIE, VICTORIA, AUSTRALIA.

FURNITURE-DRAWER.

No. 884,727.

Specification of Letters Patent. Patented April 14, 1908.

Application filed August 8, 1907. Serial No. 387,590.

To all whom it may concern:

Be it known that I, WILLIAM GRATTAN, a subject of the King of Great Britain and Ireland, &c., residing at Dookie, in the State of 5 Victoria, Commonwealth of Australia, have invented certain new and useful Improvements in Furniture-Drawers; and I do hereby declare the following to be a full, clear, and exact description of the invention, such 10 as will enable others skilled in the art to which it appertains to make and use the same.

This invention relates to furniture drawers, especially those in which fitting, materials, and workmanship result in construction where the drawers (without my attachments) are apt to jam or stick when being opened or closed, unless special attention is given to the performance of the action to 20 avoid that result. I provide fittings which can be readily attached to either old or new drawers and their casings, and which are inexpensive; these fittings prevent the drawers from sticking; in addition any drawer 25 is at will prevented from opening, except to a predetermined extent.

The accompanying drawings illustrate the invention, the scope of which includes modifications, as to number, sizes, and proportions of parts.

Figure 1 is a side view showing a drawer partly open, with the chest or casing thereof in vertical section. Part of the drawer is also broken away to show railing. Fig. 2 is a 35 plan view showing part of an open drawer, its chest or casing being in horizontal section. Fig. 3 is a front view of a corner of a chest of drawers, part of a drawer being shown in vertical section, whereby its front is not seen. Fig. 4 is a transverse vertical section showing 40 part of a drawer, drawer channel, casing rail, and casing. Fig. 5 shows a modification of Fig. 4. Fig. 6 is a vertical section longitudinally through ends of a casing rail, and shows 45 attachments to the casing. Fig. 7 is a vertical section longitudinally through a rail above the drawer illustrating means whereby the extent of drawer opening is at will limited.

50 In these views the casing is marked *a* at the drawer rear, *b* at its top, and *c* at its base. *d* is the part of the casing located over the closed drawer front. *e* is the drawer; under it at each side a V shaped groove *u*, Fig. 4, is 55 cut extending from front to rear; in this groove is fastened a V shaped metal channel

g, the rear of which is upbent behind the drawer, and has arms *q* having bearings supporting a wheel *f*. The latter is grooved, and mounted to ride on a rail *h*, on which 60 rail the channel *g* also rests. When the drawer is closed, or opened, wheel *f* at each side rotates. The rails are parallel, one to each drawer channel, the rail ends being (as at *m*, Fig. 6) bent down, pointed, and driven 65 in, or (as at *n*, that figure) flattened or recessed, and secured by a screw or the like, to casing *c*. By tilting up or slightly raising the drawer front *s*, during the opening or closing, the weight of the drawer can be 70 taken off the rails and put more on wheels *f* whereby the action will be still easier.

Each wheel *f* may have its bearings or mounting in a bracket or plate distinct from channel *g*, but the attachment can be more 75 rapidly fitted without fear of inaccuracy when the channel metal is upturned as above described. A recess in the drawer back *i* may be made in some cases for wheel *f*, or part of it, or casing *a* may be recessed at *r* as 80 shown to allow the wheel to enter and permit of the drawer going back close to casing *a*. Usually no recess is needed. The channel is of modified section in some cases as at *p*, Fig. 5 and the section of the rail is rounded 85 at the top as at *t* Fig. 5.

Over the drawer middle fixed to casing *b* is a rail *k* extending from front to rear. This rail acts as a guide to cause the drawer to open and close easily. The drawer back *i* 90 has a recess or short groove *j* in which rail *k* fits. At one or more parts rail *k* is provided with a pivoted part or stop *l* which may be longitudinal or may be transversely turned 95 to have its projecting ends in front of the drawer back *i* to prevent the drawer being opened more than to allow the back to reach the stop *l*. The inner end of the stop is shown at *o* Fig. 7, but this is one of the details which can be modified. A stop *l* at 100 the end of rail *k* is shown, but others could be added. Rail *k* is in some cases so efficient as to be usable without the use of rails *h*; and in some cases wheels *f* are omitted.

What I claim as my invention and desire 105 to secure by Letters Patent of the United States is:

1. A furniture fitting comprising a rail having means for mounting it in position over a drawer, said rail having a movable stop 110 adapted in one position to prevent withdrawal of the drawer and in another position

to form a continuation of the rail and permit withdrawal of the drawer.

2. The combination with a drawer having the top of its back recessed approximately at 5 its middle and a rail fixed to the drawer casing and fitting in said recess whereby said rail forms a guide for the drawer and said rail having one or more pivoted stops.

3. The combination of a casing having a 10 guide rail and a drawer having a recess extending substantially throughout its length and a metal channel located within said recess and fitting said guide rail, and a grooved wheel carried by said drawer at its rear and 15 running on said rail.

4. The combination of a casing having a guide rail and a drawer having a metal channel extending substantially throughout its length and fitting said guide rail, and a 20 grooved wheel carried by said drawer at its rear and running on said rail.

5. The combination of a casing having rails fixed thereto, a drawer having grooves along substantially its entire length, metal channels in said grooves sliding on said rails, 25 a rail fitted to the casing at the top of said drawer and having a stop, said drawer having a groove fitting said rail and adapted to be held in said casing by said stop.

6. A fitting for drawers comprising a metal 30 rail having means at its ends for fixing it to a casing and a metal channel adapted to be fixed to a drawer, said channel being upturned at its rear and having a roll adapted to ride on said rail.

In testimony whereof, I affix my signature in presence of two witnesses.

WILLIAM GRATTAN.
